CIRCULAR KNITTING MACHINE

Paul L. Thurston, David Nagley, and Harrison F. Hilker, Martinsburg, W. Va., assignors to Interwoven Stocking Company, New Brunswick, N. J., a corporation of New Jersey

Application January 26, 1940, Serial No. 315,666

11 Claims. (Cl. 66—14)

Our invention consists in the novel features hereinafter described, reference being had to the accompanying drawings which illustrate one embodiment of the same, selected by us for purposes 5 of illustration, and the said invention is fully disclosed in the following description and claims.

Our invention consists in improvements in a circular or seamless knitting machine for the production of a novel rib knit seamless fabric 10 having an elastic thread of rubber or Lastex incorporated in certain courses thereof, said elastic thread being united to the fabric at spaced points in each of said courses, and floated on the inner face of the fabric, between said points and across 15 one or more of the inner wales of the fabric. This novel fabric finds its greatest use in the top portions of stockings, socks and anklets, and the floated portion of the elastic thread, which is fed under a predetermined tension, while permitting 20 the desired stretch of the rib knit top and adding to the recoverability and form-fitting characteristics thereof, further provides a self-supporting function in that the floated portions of the elastic thread, which extend transversely on the 25 inner face of the fabric and inside of the inner wales thereof, slightly indent and interlock with portions of the skin of the wearer, and thus prevent the stocking, sock or anklet from slipping down the leg when worn, and render the 30 use of garters unnecessary. This improved rib knit fabric and the process of knitting the same are fully disclosed in the application of Paul L. Thurston and Leon B. Wilcox, filed in the United States Patent Office February 15, 1939, and given 35 Serial No. 256,416, and a divisional application thereof, filed June 22, 1939, and given Serial No. 280,436.

In carrying out our present invention, we preferably embody our improvements in a circular 40 or seamless knitting machine of the type in which two coaxial cylinders located one above the other are employed, in connection with a circular series of needles, each having a hook and latch at each end, the needle grooves of the coaxial cylinders 45 being in vertical alignment, so that all of the needles may be operated by suitable cam mechanism in one cylinder, as the lower cylinder, for knitting plain knit fabric, or part of the needles may be operated in each cylinder to produce rib 50 knit fabric, selected needles being transferred vertically from one cylinder to the other while retaining the stitches thereon, the stitches being transferred from the hooks at one end of such needles to the hooks at the opposite end thereof.

55 In the accompanying drawings, we have illus-

trated so much of a machine of this type made by Bentley Engineering Company at Leicester, England, and known as the "Komet" knitting machine, as is necessary for a complete understanding of our present invention shown and 5 embodied therein.

In said drawings,

Fig. 1 is a side elevation of a portion of a knitting machine embodying our invention.

Fig. 2 is an elevation taken at right angles to 10 the plane of Fig. 1.

Fig. 3 is an elevation taken at right angles to the plane of Fig. 1, but from the opposite direction.

Fig. 4 is a top plan view of the machine, parts 15 not relevant to our present invention being omitted.

Fig. 5 is a horizontal sectional view of the machine, on line 5—5 of Fig. 1, parts being cut away 20 as indicated and parts being shown in section.

Fig. 6 is an enlarged detail sectional view of the superimposed cylinders showing needles located partly in the upper cylinder and partly in the lower cylinder, and the sliders in both cylinders provided with transfer and knitting butts. 25

Fig. 7 is a plan view of the lower cylinder of the machine illustrating the thread feed fingers for feeding respectively the body thread and the elastic thread to the needles.

Fig. 8 is a diagrammatic view illustrating the 30 positions of the needles with respect to the upper and lower cylinders through the various portions of the revolution of the cylinders, dotted lines showing the manner in which the elastic thread 35 is carried around between the upper and lower cylinders during the formation of courses in which it is not incorporated.

Fig. 9 represents a diagrammatic view of the upper and lower cylinders of the machine and the knitting and transfer cam mechanisms therefor, laid out in a single plane, and showing at one end of the figure the double ended needles and the sliders for operating the same, the alternate sliders in the upper cylinder being omitted 40 for greater clearness.

Fig. 10 is a view in elevation of a sock having 45 a top portion formed of 1 x 1 rib knitting and having an elastic thread incorporated therein, by uniting it to the fabric at separated points in each of certain, preferably spaced courses, and floating it on the inside of the fabric and across the inner faces of one or more intervening inwardly extending rib wales, produced by our improved machine.

Fig. 11 represents an enlarged view of a por-

55

tion of the rib top broken away, and showing the interior thereof.

Fig. 12 is a diagrammatic horizontal sectional view of the rib top fabric illustrated in Figs. 10 and 11.

In Figs. 10, 11 and 12 we have illustrated the fabric (which forms no part of our present invention) which our improved machine is desired to produce. In Fig. 10, for example, there is shown a sock, indicated at A, provided with a top portion T, of rib knitting, in this instance 1 x 1 rib, having elastic thread, indicated at E, incorporated in a plurality of courses, in this instance, spaced from each other by a plurality of courses not containing the elastic thread, which is floated vertically from one elastic thread containing course to the next. The elastic thread in each of the courses containing it is united to the fabric at spaced points, indicated at ex, and floated, as at ey, on the inner face of the fabric, and across the inner faces of intervening inwardly extending rib wales, as clearly indicated in the drawings, particularly Fig. 12. In Fig. 12, B indicates the body thread, forming the rib fabric, here shown as 1 x 1 rib, b' indicating the outwardly extending rib wales and b2 indicating the inwardly extending rib wales. E represents the elastic thread which in this instance is fed so that it comes under the latch of every fourth needle of the needles in the lower cylinder and is held united to the fabric by the adjacent sinker wales at opposite sides of the selected outwardly extending wales, as indicated at ex, while the floated portions ey of the elastic thread extend on the inner face of the fabric across the inner faces of the inwardly extending rib wales b2 between said points of union, where said floated portions can come directly into contact with the skin of the wearer, and by slightly indenting the same, interlock with the skin and support the top, and therefore the leg of the stocking on the leg.

In Fig. 10 the leg and top of the foot of the stocking is shown as composed of conventional 6 x 3 rib, but it will be understood that by transferring selected needles, under the control of the usual pattern mechanism present in machines of the type herein shown, from one cylinder to the other, the leg of the stocking may be knit in any desired type of rib knitting, or where all the needles are located in the lower cylinder, the leg and top of the foot may be knit by plain knitting if desired. In any case the heels and toes will be formed in the usual manner, in accordance with the normal operation of the machine.

In the machine illustrated in the accompanying drawings, 10 represents the lower knitting cylinder and 20 the coaxial upper cylinder, each provided with vertically movable sliders, 11 and 12 respectively, in the cylinder grooves, each of said sliders being provided with a transfer butt, or 12' and 22 or 22a respectively, and knitting butt, 13 or 13a and 23 respectively, and having at the end adjacent the opposed cylinder means for engaging and holding one of the double ended needles 30, each of which has a hook and latch at each end, and is adapted to be operated in connection with the sliders of both cylinders, as is customary in the "Komet" machines above referred to, and as illustrated in Figs. 6 and 9.

Fig. 7, which is a plan view of the lower cylinder 10, shows the relative locations of the thread feed finger b, for the body thread B, and the thread feed finger e for the elastic thread E, which latter is movable into and out of operative

position under the control of the pattern mechanism, the inoperative position being indicated in dotted lines in Fig. 7.

In the specific knitting machine illustrated in the accompanying drawings, the needle cylinders are arranged for knitting the top of the stocking, sock or anklet of 1 x 1 rib, although this is not essential, and therefore alternate needles are engaged and controlled at all times during the knitting of the top by the sliders of the lower cylinder, and the intervening needles are normally engaged and operated by the sliders in the upper cylinder, taking the body thread and forming the 1 x 1 rib fabric, the sliders of the upper cylinder being operated to that end by the upper cylinder knitting cam mechanism, and the lower cylinder sliders being operated by the lower cylinder knitting cam mechanism, in the usual manner. The machine is constructed to incorporate a separate continuous elastic thread of rubber or Lastex, into certain courses of the 1 x 1 rib knitting, in this instance in every fourth course, and to unite the elastic thread to the fabric at every fourth exterior or outwardly extending wale (or every seventh wale of the course) said outwardly extending wales being formed by the needles of the lower cylinder, so as to form the floats of elastic thread on the inner face of the fabric and across the inner faces of certain inner wales thereof. It is obviously advantageous to space the courses containing the elastic thread, as its use adds to the cost of production, but it is to be understood that the particular spacing of the wales, and the particular spacing of the points in each elastic thread bearing course where the elastic thread is secured to the fabric, may be varied if desired.

As the elastic thread, as shown and hereinafter described, is fed to selected needles of the lower cylinder needles, which form the outwardly extending rib wales, and the floated portions must lie on the inner faces of the intervening outwardly extending rib wales, and as the elastic thread at the termination of each course containing it must be carried around by the cylinder while held in the thread finger e, in its inoperative position, we provide means for transferring the needles of the upper cylinder to the lower cylinder, during a portion of each course of knitting the top, and needle selecting means, operative while all the needles are in the same cylinder, place the spaced selected needles in position to receive the elastic thread. In this instance this is accomplished by bringing the selected needles to a higher elevation than the remaining needles, and thereafter bringing all the needles to the same elevation while in the same cylinder, to insure that the needles of the upper cylinder, which form the inwardly extending rib wales, shall be outside of the floated portions of elastic thread. This provides a clear space between the cylinders, adjacent to the feed finger e for the elastic thread while all the needles are in one cylinder, to permit the portion of the elastic thread between the thread guide e and the last stitch of a course containing it to remain attached to the fabric during the formation of intervening courses not containing elastic thread, and thus providing that the elastic thread may be floated vertically from one course containing it to the next, and be continuous throughout the courses of the top containing it. The needle selecting mechanism, as hereinafter explained, is inoperative during the formation of intervening courses during the knitting of which only the body thread is fed to the needles while present in both cylinders.

ders, and at a point remote from the elastic thread feed finger. During the formation of these intervening courses the portion of the elastic thread between the termination of the last course containing it and the feed finger *e*, can be carried around the cylinder over the tops of the needles without encountering any obstacle.

In the description of the machine and its operation, we will refer to the needles which are located in the upper cylinder during the formation of the rib fabric, as the upper cylinder needles whether they are in the upper cylinder, or temporarily transferred to the lower cylinder during a portion of each course.

15 The upper cylinder is provided with a stationary cam ring *24* and the lower cylinder is provided with a stationary cam ring *14*. Fig. 9 shows the inner faces of the cam rings as they would appear if split vertically and laid out in a single plane, and the arrangement and functions of the cams which cooperate in producing the unique rubber incorporated rib fabric will now be described.

As the cylinders rotate the needles in traveling between the points indicated by the arrows *R*, *R'* in the diagram Fig. 8, will be alternately located in the upper and lower cylinders, and will receive the body thread *B* from the feed finger *b*, alternately in the lower hooks of the upper cylinder needles and the upper hooks of the lower cylinder needles and will knit 1 x 1 rib stitches in accordance with the normal operation of a knitting machine of this type. *I* represents a transfer cam movable into and out of operative position with respect to the transfer butts of the upper cylinder sliders to transfer the needles connected therewith to the lower cylinder. This cam *I* is shown as carried by a radially movable plunger *1a*, operated by mechanism hereinafter described. 40 This cam is moved to operative position during the formation of the top.

At the point indicated at *R'* the transfer butts of the upper cylinder sliders, after their needles have drawn their rib stitches, and have cast off the stitches in the same inner wales of the preceding course, will engage the transfer cam *I* and be moved downwardly so as to place the needles carried thereby in control of the corresponding sliders of the lower cylinder, and the needles will slide vertically through the stitches held thereon until they reach the point indicated at *R* (Figs. 8 and 9) when they are returned to the upper cylinder and to the control of the sliders thereof. This provides an open space, indicated at *S* in Fig. 9 between the upper and lower cylinders where all the needles are in the lower cylinder, and the elastic thread is free to extend through this space, and change its position between the feed finger *e* and the last needle of a previous course in which the elastic thread is united to the fabric, as indicated by the dotted lines in Fig. 8.

After the needles of the upper cylinder have been placed in charge of the corresponding sliders of the lower cylinder, a needle separation is effected in those courses in which an elastic thread is fed to selected needles, in this instance by the following means. Cam *2* (Fig. 9) is positioned so that it will engage the knitting butts *13* or *13a* of the sliders of the selected needles of the lower cylinder needles in the courses in which elastic thread is fed thereto. The sliders of the lower cylinder are provided with long and short transfer butts, *12* and *12'*. The butts of the

selected needles, which are to receive the elastic thread have short transfer butts *12*. These needles are in this instance every fourth needle of the lower cylinder needles or every seventh needle of the circular series. The sliders in the lower cylinder for all the remaining needles of the lower cylinder and upper cylinder have the long transfer butts *12'*. A special draw down cam *3* is provided to engage the long transfer butts *12'* without engaging the short butts *12* of the selected needles, said cam being located below the cam *2*, and being very considerably steeper. As the cylinders rotate and bring the sliders into engagement with the cams *2* and *3* the sliders of all the needles, except the selected needles, will be drawn down by cam *3* faster than the sliders for the selected lower cylinder needles will be drawn down by cam *2*, engaging the knitting butts *13* and *13a* thereof, thus leaving the empty hooks of the selected needles momentarily above those of the unselected needles, and in position to receive the elastic thread *E* from the thread guide *e* at the point indicated at *ex* in Fig. 9, after which all needles come to the same level, still holding their loops of inelastic or body thread. As the selected needles, after receiving the elastic thread in their hooks, are drawn downward by cam *2*, they will carry the float portions of the elastic thread to the rear of the unselected needles, so that said float portions will be on the inner face of the rib fabric and will extend across the inner faces of the intermediate inwardly extending rib wales formed by the needles of the upper cylinder. The cam *3* is movable into and out of operative position by suitable mechanism hereinafter described, and is preferably mounted on a radial plunger *3a*.

It will be understood from the foregoing that in knitting the 1 x 1 rib fabric courses in which the elastic thread is not introduced the cam *3* will be pushed inward into its innermost operative position to engage both the long butts *12'* and short butts *12* of the sliders for all the needles, and all the needles will be drawn down uniformly by the cam *3*, and no needle separation will take place. In those courses (for example every fourth course) in which the elastic thread is to be introduced, the cam *3* will be moved into its intermediate operative position to engage only the long transfer butts *12'* of the unselected needles, the selected needles being drawn down by cam *2*, thus drawing the needles acted on by cam *3* downward more rapidly than the selected needles, which receive in their hooks the elastic thread while retaining the loop of body thread previously formed at the main throat.

It is also to be understood that the cams *2* and *3* are so constructed that while they effect the needle separation to permit the feeding of elastic thread to the selected needles, these cams *2* and *3* do not draw down the needles far enough to cast off the loops of body thread carried thereby. The needles are, however, drawn down far enough to close their latches.

All the needles are now raised by their riser cams, indicated at *4* and *5* in Fig. 9, the unselected needles passing in front of the float portions of the elastic thread. As the selected needles rise the elastic thread will effect the opening of their latches. In order to insure the opening of the latches of the remaining needles, a latch opener *6* is provided, as shown in Figs. 1 and 4. The latch opener performs an important function in this machine. It will be understood that when a machine of this type is used in the ordi- 75

nary and known manner to produce 1 x 1 or other rib fabric, the hooks at the upper ends of the needles of the upper cylinder are not called into action, and when said needles are transferred 5 to the lower cylinder to produce plain knit fabric, the hooks at the upper ends of the upper cylinder needles are fed body thread at the throat and as they rise in being retransferred to the upper cylinder, the stitches held in the upper hooks 10 of these needles will open the latches and insure proper reengagement with the sliders of the upper cylinder.

In the machine constructed and operating in accordance with our invention, however, the 15 needles of the upper cylinder are transferred to the lower cylinder in every course during the knitting of the rubber incorporated rib fabric after they pass the throat, or main knitting station, and are returned or retransferred to the 20 upper cylinder before any thread can be fed to the upper hooks. The latch opener is, therefore, provided to insure the opening of the latches of the upper hooks of the upper cylinder needles in order that they may properly engage the sliders 25 of the upper cylinder and prevent the breakage of needles and sliders which would otherwise result.

The transfer butts of the needles of the upper cylinder series now engage the transfer cam 8a (Fig. 9) while at the same time the corresponding sliders in the upper cylinder are pushed downward by transfer cam 8, thus transferring the upper cylinder needles to the upper cylinder sliders and the transfer butts of the upper sliders are then engaged by the riser cam 1, which completes the transfer of the needles of the upper cylinder thereto, and positions their lower hooks to again take the body or inelastic yarn at the main throat, and continue knitting 1 x 1 rib in conjunction with the needles of the lower cylinder.

In knitting the next course or courses (in this instance we provide for three intervening courses in which the elastic thread is not incorporated) 45 the cam 3 will be pushed inward far enough to engage the transfer butts of all the needles (all the needles being then in the lower cylinder). Thus all needles will be drawn down by cam 3 and there will be no selection, and hence the 50 portion of the elastic thread between the finger e and the last stitch in which it is incorporated will be free to pass over the tops of the needles, without encountering any raised needle, and without becoming incorporated in the fabric, during 55 the knitting of such intervening course or courses, as indicated in the dotted lines in Fig. 8. The stretch of the elastic will accommodate it to these different positions, but a yielding take-up of any usual or desired kind may be employed 60 if desired.

When the next elastic thread incorporated course is knit the cam 3 is withdrawn to a position in which it engages the long transfer butts 12' only, thus effecting the needle separation by 65 leaving the selected needles to be drawn down more slowly by cam 2, and thus incorporating the elastic thread as previously described. This enables us to use a continuous elastic thread throughout the top of the stocking or sock, which is floated downwardly from one course to the next 70 course in which it is incorporated.

Referring to the drawings, Figs. 1, 2, 3 and 4, the mechanism for operating the transfer cam 1, hereinbefore referred to, will now be described. 75 On the main pattern drum shaft 40 is mounted

a drum 41 provided with a cam 42, which controls the position of the transfer cam 1. This cam 42 actuates a lever 43 pivoted to the machine body at 44, and provided at one end with a downwardly extending portion 45 to engage the 5 cam 42. The other end 46 of the lever 43 is connected by a rod 47 with a bell-crank 48 pivoted to a bracket 49 secured to the upper cylinder plate 50 and having a depending arm 51 at all times in contact with a horizontal push rod 52 10 extending through the bracket 49 and engaging the radial plunger 1a of the cam 1, for the purpose of moving the cam inwardly, as hereinbefore described, and permitting it to be moved outwardly at the proper times, by a suitable re- 15 tracting spring, indicated at 1b. This cam 1 is brought into operation at the commencement of the knitting of the top of the stocking and remains in operative position until withdrawn at the conclusion of the knitting of the top portion. 20

The mechanism for operating the upper cylinder cam 1x for the return of the sliders of the upper cylinder after they have transferred their needles to the grooves of the lower cylinder, is as follows. A cam 61 on the main pattern drum 25 60 engages a push rod 62 and actuates a lever 63, one arm of which carries a horizontally movable pin 63a which, in operative position, engages cams 64 and 64a on the face of a cam disc 65 on the main drive shaft 66, thereby causing said 30 pin to impart horizontal oscillating movement to a pawl lever, indicated at 63b, causing it to effect the rotation of a ratchet wheel 63c on a vertical shaft 63d, thereby rotating a series of auxiliary pattern cams 67, 67a, 67b, 67c and 67d. This 35 mechanism constitutes no part of our invention and will not be particularly described.

The cam 67c of the auxiliary pattern mechanism operates a plunger 68, see Fig. 3, engaging a horizontal lever 69, pivoted between its ends to a bracket 69a. One end of the lever 69 engages the plunger 2a to which the cam 2 is connected. The other end of the lever 69 simultaneously engages the lower end of a vertical lever 70, the upper end of which operates the plunger 1xa of the cam 1x, so that both of the cams 1x and 2 are moved inwardly into operative position at the same time, the pattern cam also permitting them to move outwardly at the proper time under the influence of their respective springs surrounding the plungers to which the cams are connected. The cams 1x and 2 will also be brought into operation at the beginning of the knitting of the top and will remain in operative position until the completion of the top. 50

Mechanism is provided, as hereinafter described, to move the cam 3 into this intermediate position for each course of stitches containing the elastic thread. At the conclusion of each of said courses during the knitting of the top of the sock or stocking, the cam 3 is pushed inward to its innermost position, where it will engage both the long and short butts 12' and 12, and draw down all of the needles to the same extent including the previously selected needles, which therefore 65 do not take the elastic thread for one, two or more courses, as preferred. It will be understood that at the conclusion of the knitting of the top containing the elastic thread in selected courses, the cam 3 will be withdrawn to its outermost position and remain inoperative until the top of the next sock or stocking is to be knit, when it is again moved inwardly into one or other of its operative positions. 70

In order to permit the cam 3 to be pushed in- 75

ward without injury to the butts 12, 12' of the sliders, the clearing cam 93 which follows the main knitting cams, indicated at K, K', and K2 of usual form, is provided with a radially movable portion 93a which is capable of being moved radially into and out of operative position. This movable portion 93a of the clearing cam 93 is withdrawn momentarily immediately before the commencement of the top portion of the sock or stocking, permitting the knitting butts 13, 13a to pass below the upper portion of the cam 93, thus allowing a certain number of the sliders to pass the selecting cam 3 with their butts 12, 12' below said cam, as indicated by a dotted line in Fig. 9. This permits the cam 3 to be pushed in to either its intermediate or innermost position between the knitting butts 13, 13a, and the butts 12, 12' of the sliders, according to whether the next course contains the elastic thread or not. As soon as the selecting cam 3 has been pushed in to the desired position, the movable portion 93a of the clearing cam is moved inward to its innermost position, where it remains during the knitting of the stocking.

In the machine illustrated in the accompanying drawings, the temporary withdrawal of the movable portion 93a of the clearing cam 93 is accomplished by the following mechanism. A cam 80, see Fig. 1, on the pattern drum 60, engages a lever 81 upon which rests the lower end of a vertically movable rod 82 mounted in guides 83, which rod carries a clamp 84 to which is secured one end of a Bowden wire 85, the casing of which is secured to the frame, as indicated at 86. To avoid confusion, the wire and casing are both indicated by the numeral 85. The Bowden wire 85 is carried around the machine and connected to a plunger 87, to which the movable portion 93a of the clearing cam 93 is connected, as indicated in Fig. 3. This permits the desired withdrawal of said movable portion 93a of the clearing cam 93 to allow the selecting cam 3 of the selecting cam mechanism to be moved inward, under the control of the pattern drum 60, without injury to the butts 12, 12' of the sliders.

With reference to the needle selecting cams 2 and 3, it has already been noted that cam 2 is operated by the same mechanism which operates cam 1x, and will be brought into operative position at the same time as cam 1x, at the beginning of the knitting of the top, and will remain in operative position until the completion of the top. The means herein shown for the operation of cam 3 is as follows, see Figs. 1, 2, 3 and 5. A shaft 101 is mounted in a bracket secured to the side frame of the machine and operated from the driving shaft in any suitable manner. This shaft 101 carries a cam wheel 102 for controlling the position of the needle selecting cam 3. A cam lever 103 is mounted on a pivot 104 secured to the bracket and has a portion 105 to engage the cam wheel. A retracting spring 114 holds the portion 105 of the lever 103 in engagement with the cam wheel 102. The other end of the lever 103 being connected by a link 106 to one arm 107 of a bellcrank mounted in a bracket 108, and having a depending arm connected with a short horizontal rod 109, the end of which engages the plunger 3a of the selecting cam 3, for moving the cam into one or other of its radial positions, according to the elevations of the cam wheel 102, the cam 3 being withdrawn when permitted by the cam wheel, by means of the usual retracting spring operatively connected with its plunger. The cam wheel is provided with different levels

around its periphery, so that when the cam lever 103 is in engagement with the portion 110, as shown in Fig. 1, for example, the selecting cam 3 will be moved inwardly so as to engage the butts 12 and 12' of the selected and unselected needles, drawing them all down at the same rate of travel. When the cam lever drops down to the portion 111 having the intermediate elevation, the selecting cam will be moved outwardly by its spring so that only the long butts 12' on the sliders of the unselected needles will be brought down by the cam 3, leaving the selected needles to be moved downwardly at a slower rate by the cam 2, and thus placing their hooks in a higher position than the hooks of adjacent needles, to receive the elastic thread. When the cam lever 103 engages the portion of the cam wheel 102 having the lowest level, indicated at 102a as hereinafter described the selecting cam will be completely withdrawn from engagement with the butts 12, 12' on the sliders, and will be inoperative during the knitting of the leg and foot of the stocking and until the top portion of the leg of the next consecutive sock or stocking is commenced.

In Fig. 9 of the drawings we have illustrated a vertically adjustable drawdown cam, indicated at 2b, mounted on a vertically movable slide 2c in the cam block, for the purpose of adjusting the downward movement of the selected needles after they leave the selecting cam 2 to the level of the unselected needles drawn down by cam 3. Ordinarily this cam 2b is adjusted so that after the selected needles take the elastic thread they will not be drawn down far enough to draw a stitch of rubber through the loop of inelastic thread held on the needle and will not cast off the said loop of inelastic thread and cam 3 is also adjusted so that it will not draw down the unselected needles far enough to cast off stitches of inelastic thread held thereon. The movement of the cam 2b is controlled in this instance by a cam ring 120, see Fig. 1, on the shaft 63d previously described, which engages a cam operated lever 121 pivotally mounted on a frame and having its outer end engaging the under side of a lever 123 pivotally mounted to the stationary cam ring 14, the other end of which operatively engages the drawdown cam 2b. As the needles pass the drawdown cam 2b, the knitting butts 13 and 13a of all the needles will engage the riser cams 4 and 5, which will bring the needles to the same level, interlacing the elastic thread so that it passes in front of the selected needles and in rear of the unselected needles, and raising all of the needles. It is then necessary to retransfer the needles of the upper cylinder to the sliders of the upper cylinder in order to knit a further course of 1 x 1 rib. For this purpose we prefer to employ a cam 8 on the upper cam cylinder, see Fig. 9, which engages in this instance, the long butts 22a on every other slider 21, depressing these alternate sliders into position to receive their needles from the corresponding sliders of the lower cylinder, the intervening sliders passing across without being depressed, as indicated by the dotted line in Fig. 9. In this figure, for simplification, we have omitted the intermediate sliders which do not at any time receive an upper cylinder needle in the knitting of 1 x 1 rib, but it will be understood that in practice each groove of each cylinder is provided with a slider. As the alternate sliders 21 of the upper cylinder descend, the butts 12 and 12' of the sliders of the lower cylinder will be raised by cam 8a in the lower cam block sufficiently to cause the

needles of the upper cylinder to engage the sliders for the upper cylinder which have been depressed by cam 8 in the upper cam block, transferring the needles of the upper cylinder to the corresponding upper sliders 21. The long butts 22a of the upper cylinder sliders having received their respective needles, are then carried upwardly by a cam 7, see Fig. 9, thus bringing all of the needles of the upper cylinder in proper position to coat with the needles of the lower cylinder in the formation of 1 x 1 rib. These cams 8, 8a, operate in the manner usual in Komet machines and in themselves constitute no part of our present invention.

15 After the selected needles have received the elastic thread as previously described, and the needles have been raised by the riser cams 4 and 5, it will be understood that the unselected needles, while retaining their loops of inelastic thread, have also been lowered by one or other of the drawdown cams 2 and 3 far enough to partially or wholly close their latches without however casting off the previously formed loops of inelastic thread. It is necessary, therefore, to insure that the latches of the unselected needles, alternate ones of which are upper cylinder needles, shall be opened in order that they may properly engage their upper cylinder sliders and also that the latches of the lower cylinder needles 30 of the unselected groups, shall be opened in order that they may receive the inelastic thread for the next course.

Therefore we provide the latch opener 6, as previously described, which is thrown into operative position to open the latches of all the needles, and which is preferably brought into operative position by the following mechanism. Mounted on the pattern drum 41 is a cam 124 for controlling the operation of the latch opener. 40 This cam operates a lever 125 pivotally connected to the gear casing at 126 and provided with a depending portion 127 to engage the cam. This lever 125 is connected by link 128 with one arm of a bellcrank 129 pivotally mounted on a bracket 45 130 secured to the base plate. The other arm of the bellcrank is connected to a Bowden wire which, with its casing, is indicated at 131, the casing being connected to the machine frame and the Bowden wire connected at one end to the bell- 50 crank 129, and at its other end to one arm of a bellcrank 134, see Fig. 5, the other arm of which bears against a screw 136 in a horizontal plate 137 pivotally mounted on a bracket secured to the base plate and carrying the latch opener 6 55 adjustably secured thereto. The plate 137 is provided with a retracting spring 141 which swings the latch opener into position to engage the latches of the needles when the depending portion 127 of the cam lever 125 passes off of the cam 60 124. The latch opener is ordinarily permitted to remain in operative position during the knitting of the entire top.

We prefer to provide mechanism for disengaging the needle selecting pattern mechanism and 65 the connections between the same and the needle selecting cams 2 and 3 during the knitting of the leg and foot of the stocking, and to this end the pattern drum 41 on the pattern drum shaft 40 in this instance is provided with a cam 150 which 70 engages a downwardly extending projection 153 at one end of a lever 151 pivotally mounted on the gear casing and having at its opposite end a downwardly extending portion 151a which, as indicated in Fig. 2, engages a lever 154 mounted on 75 the bracket 100 and having a curved portion 154a

operatively engaging the side of the pawl lever 103 so as to move it laterally on its pivoted shaft 104 against a coil spring 156. This has the effect of disengaging the pawl from the cam wheel 102 and cause the cam engaging portion of the lever 103 to drop down on the auxiliary cam portion 102a of the cam wheel which is of the smallest diameter, as heretofore stated, for the purpose of completely withdrawing the selecting cam 8 from operative relation with the sliders and entirely 10 out of range of the cam portions 110 and 111 of highest and intermediate elevations. The auxiliary cam portion 102a is of substantially uniform diameter, as shown in Fig. 1, except for a portion 102b which has its periphery coincident 15 with the cam portion 110 of the cam wheel 102, and is provided with the cam grade 102c. So long as the lever 103 is in engagement with the circular portions of the auxiliary cam portion 102a the needle selecting mechanism operated by 20 the lever 103 and its connections will remain inoperative, which time corresponds with the conclusion of the top of the stocking and the knitting of the leg and foot thereof. When the top of the next succeeding sock or stocking is to be knit the 25 lever 103 will be engaged by the cam grade 102c and will be raised to the level of the adjacent cam portion 110 of the cam wheel 102, at which time the cam 150 on the pattern shaft 40 will have permitted the upper end of the lever 151 to drop 30 off of the cam and release the lever 154, permitting the retracting spring 156 to shift the lever 103 sideways and placing it again in operative relation with the cams 110 and 111 of the cam wheel 102. 35

It has been previously stated that the cam wheel 102 on the stub shaft 101 is operated by a connection with the main driving shaft 66. In this instance the rotation of the cam wheel 102 and the auxiliary portion 102a is secured by the 40 ratchet construction, which comprises in this instance the following parts. On the stub shaft 101 is mounted a ratchet wheel 169 shown in full lines in Fig. 2 and in dotted lines in Fig. 1. This ratchet is engaged by a pawl 168 carried by an oscillating plate 165 which is connected by a link 167 with a lever 163, pivoted to the machine at 164 and provided on the opposite side of the pivot with the friction roll 162. This friction roll is in position to be engaged by a cam 161 on a cam 50 wheel 65, shown in dotted lines in Fig. 1, and secured to and rotating with the main driving shaft 66. When the cam 161 comes in contact with the friction roll at each revolution of the main driving shaft, the ratchet plate carrying the 55 pawl 168 will be operated to effect the partial rotation of the cam wheel 102 and auxiliary cam wheel 102a.

In order to prevent the unnecessary operation of this mechanism during the knitting of the leg 60 and foot of the stocking or a portion thereof, we provide a lockout mechanism for holding the lever 163 in position to remove the friction roll 162 from the path of the cam 161. In the present instance we have shown for this purpose a lockout lever 174, see Fig. 1, pivotally mounted at 173 on the machine frame and extending downwardly therefrom into a position adjacent to a lockout pin 163a on the lever 163. The lever 174 is provided with an adjustable lockout stop 175 in the 70 form of a set screw with locknut for engaging the pin 163a and holding the lever 163 in such position that the friction roll 162 will not be engaged by the cam 161, previously described. This lockout lever 174 is provided with an up- 75

wardly extending weighted arm 172 which is engaged by a cam 171 on a pattern drum 170 mounted on the main pattern shaft 40, see Figs. 2 and 4. In Fig. 1 the parts are shown in the 5 positions which they occupy at the commencement of the knitting of a sock and the first operation which takes place is the engagement of the arm 172 by the cam 171, which disengages the lockout arm 174 from the pin 163a on the rack 10 lever 163 for operating the cams 102, 102a. At this time the lever 103 will be in engagement with the portion 102a of smallest diameter at a point sufficiently in advance of the elevating cam 102b, previously described, to permit the formation 15 of a predetermined number of courses of 1 x 1 rib knitting to constitute the selvage or anti-ravel of the top, which may be of any desired form and has no bearing on the present invention. Thereupon the lever 103 encounters the lifting cam 20 grade 102b, permitting the lever 103 to be shifted over to the main cam wheel 102 which, during the courses of the top will, by reason of its highest and intermediate cam portions 110 and 111, previously described, shift the selecting cam 3 to its 25 innermost position for knitting a plurality of courses without elastic, and thereafter into its intermediate position for the feeding of the elastic thread to the spaced selected needles and the production of floats of the elastic thread on the 30 inner face of the fabric and across the intervening inwardly extending rib wales, as hereinbefore described.

We desire to have it understood that the specific pattern mechanism and the connections 35 therefrom to the various parts controlled thereby shown in the accompanying drawings and described in the preceding portion of the specification represent constructions which have been actually employed in a particular machine, but 40 the operation of the various pattern controlled parts may be accomplished by different types of pattern mechanism and different mechanical connections therefrom to the parts to be controlled, according to the ideas of different constructors of knitting machinery, without departing 45 from the spirit of our invention, and we do not desire to be limited to the exact forms of pattern mechanism or the connections therefrom to the parts to be controlled thereby, that are 50 herein shown and described for the purpose of presenting a completely operative mechanism.

While it is not important to the understanding of our present invention, it will be understood that the sliders 11 of the lower cylinder are provided 55 with knitting butts 13, 13a, of different lengths, that is to say, half of the circular series of needles which knit the heel and toe pockets by narrowing and widening have their sliders provided with the long butts, 13a, while the remaining 60 half of the needles knitting the front portions of the leg and top of the foot are provided with the short butts 13. The long butts 13a cooperate with the usual picker mechanism during the narrowing and widening of the heel and toe pockets in the usual manner.

As previously stated the elastic thread E is fed under a predetermined tension, and in Fig. 1 we have indicated at D a suitable tension device 70 comprising in this instance a pair of discs t between which the elastic thread E passes, said discs being compressed together by means of a spring t', the tension of which can be adjusted by a threaded adjusting nut t2. Other forms of 75 tension means may, however, be used to apply

tension to the elastic thread. The degree of tension may be varied, but we prefer to apply sufficient tension to the elastic thread during the feeding thereof to stretch it and hold the floated portions on the inner face of the rib fabric 5 stretched during the knitting, and to a sufficient extent so that when the fabric is removed from the machine these floated portions will remain without slack in the undistended condition of the top of the stock or stocking. It will also be seen 10 that these floated portions of the elastic thread being on the inner face of the fabric and extending across the inner faces of the inwardly extending rib wales between the wales at which the elastic thread is secured to the fabric, will 15 present substantially continuous horizontal beads extending entirely around the inner face of the top, which will come directly into contact with the skin of the wearer and will slightly indent the skein and interlock therewith, so as to retain the top and the connected leg of the stocking in position on the leg without the necessity of any garter or other support. The tensioning device may in some instances be so adjusted that after 20 the fabric is removed from the machine the floated portions of the elastic thread will be under sufficient tension to draw the adjacent inner and outer rib wales of the fabric into closer relation than they would naturally be held due to the rib 25 formation produced by the knitting of the inelastic thread in the rib form which of itself has a tendency to draw the adjacent inner and outer rib wales toward each other, but not necessarily into close contact.

The thread feed finger e for feeding the elastic thread during the knitting of the top portion of the sock or stocking is in this instance the usual thread feed finger provided in the Komet machine for the feeding of a secondary thread when desired, and it is thrown into and out of operative position by mechanism controlled by the pattern mechanism, in the manner usual in the Komet machine. As the specific mechanism for operating this finger forms no part of our present invention, it will not be specifically described 45 herein.

It will also be understood that while we have described the machine for carrying our invention into effect as arranged for the production of 50 1 x 1 rib, it is not limited to this particular character of rib knitting, as the machine may be so set as to produce other forms of rib knitting with the elastic thread secured to the fabric in spaced wales and extending between its points of attachment on the inner face of the fabric and across the inner faces of intervening inwardly extending 55 rib wales.

What we claim and desire to secure by Letters Patent is:

1. The combination in a circular knitting machine of the type employing coaxial superimposed knitting cylinders, separate knitting cam mechanisms therefor, means for establishing relative rotation between the cylinders and knitting cam mechanisms, a circular series of needles, each provided with hook and latch at each end, and a slider for each needle in each cylinder provided with cam engaging butts, of mechanism adjacent to the knitting cam mechanisms for continuously feeding a non-elastic body thread 60 to both the upper and lower cylinder needles, to knit successive courses of rib knitting, transfer mechanism for transferring all the upper cylinder needles to the lower cylinder during a portion of each of a plurality of relative rota- 65 70 75

- tions of the cylinders and cam mechanisms, needle selecting cam mechanism for engaging the sliders of the lower cylinder, for bringing the hooks of selected needles to a different elevation from those of unselected needles, mechanism for feeding an elastic thread to the selected needles, cam mechanism for bringing the hooks of all the needles to the same level and bringing the unselected needles outside of float portions of the elastic thread between selected needles, and transfer cam mechanism for retransferring the needles of the upper cylinder thereto before they reach the feeding point of the non-elastic thread in each course of knitting.
- 15 2. The combination in a circular knitting machine of the type employing coaxial superimposed knitting cylinders separate knitting cam mechanisms therefor, means for establishing relative rotation between the cylinders and knitting cam mechanisms, a circular series of needles each provided with hook and latch at each end, and a slider for each needle in each cylinder provided with cam engaging butts, of mechanism adjacent to the knitting cam mechanisms for continuously feeding a non-elastic body thread to both the upper and lower cylinder needles, to knit successive courses of rib knitting, transfer mechanism for transferring all the upper cylinder needles to the lower cylinder during a portion of each of a plurality of relative rotations of the cylinders and cam mechanisms, needle selecting cam mechanism for engaging the sliders of the lower cylinder, for bringing the hooks of selected needles to a different elevation from those of unselected needles, mechanism for feeding an elastic thread to the selected needles, cam mechanism for bringing the hooks of all the needles to the same level and bringing the unselected needles outside of float portions of the elastic thread between selected needles, and transfer cam mechanism for retransferring the needles of the upper cylinder thereto before they reach the feeding point of the non-elastic thread in each course of knitting, and means for throwing the needle selecting cam mechanism into and out of operation to permit the knitting of a course or courses of rib knitting without the elastic thread between courses containing the elastic thread, the portion of the elastic thread between its feeding means and the last stitch containing it extending above the hooks of all the needles during the portion of each rotation of the machine in which the upper cylinder needles are in the lower cylinder.
- 55 3. The combination in a circular knitting machine, provided with upper and lower coaxial knitting cylinders, separate stationary knitting cam mechanisms therefor, means for rotating said cylinders, a circular series of needles each provided with a hook and latch at each end, and a slider for each needle in each cylinder provided with knitting and transfer butts, of mechanism adjacent to the knitting cam mechanisms for feeding a non-elastic body of thread to both the upper and lower cylinder needles to knit successive courses of rib knitting, transfer mechanism for transferring all of the upper cylinder needles to the lower cylinder after the needles have received the non-elastic thread in a plurality of rotations of the cylinders, the sliders of the lower cylinder having short transfer butts for spaced selected needles and long transfer butts for intermediate unselected needles, needle selecting mechanism comprising a drawdown cam

for engaging the knitting butts of the lower cylinder sliders for the selected needles, and a second drawdown cam movable into position to engage the long transfer butts of the lower cylinder sliders, for the unselected needles, and having a steeper pitch than the first mentioned drawdown cam, to bring the hooks of the unselected needles to a lower level than those of the selected needles, mechanism for feeding an elastic thread to the hooks of said selected needles, cam mechanism for bringing the hooks of all the needles to the same level, and bringing the unselected needles on the outside of the floated portions of the elastic thread between the selected needles, and transfer mechanism for returning the upper cylinder needles to the upper cylinder before they reach the feeding point of the non-elastic body thread in each course of knitting.

4. The combination in a circular knitting machine, provided with upper and lower coaxial knitting cylinders, separate stationary knitting cam mechanisms therefor, means for rotating said cylinders, a circular series of needles each provided with a hook and latch at each end, and a slider for each needle in each cylinder provided with knitting and transfer butts, of mechanism adjacent to the knitting cam mechanisms for feeding a non-elastic body thread to both the upper and lower cylinder needles to knit successive courses of rib knitting, transfer mechanism for transferring all of the upper cylinder needles to the lower cylinder after the needles have received the non-elastic thread in a plurality of rotations of the sliders of the lower cylinder having short transfer butts for spaced selected needles and long transfer butts for intermediate unselected needles, needle selecting mechanism comprising a drawdown cam for engaging the knitting butts of the lower cylinder sliders for the selected needles, and a second drawdown cam movable into position to engage the long transfer butts of the lower cylinder sliders for the unselected needles, and having a steeper pitch than the first mentioned drawdown cam, to bring the hooks of the unselected needles to a lower level than those of the selected needles, mechanism for feeding an elastic thread to the hooks of said selected needles, cam mechanism for bringing the hooks of all the needles to the same level, and bringing the unselected needles on the outside of the floated portions of the elastic thread between the selected needles, and transfer mechanism for returning the upper cylinder needles to the upper cylinder, before they reach the feeding point of the non-elastic body thread in each course of knitting, and means for shifting the second mentioned drawdown cam into position to engage the transfer butts of all the needles, to prevent needle selection, and permit the elastic thread to be carried around the cylinder, above the hooks of all the needles while in the lower cylinder to form courses composed only of the inelastic thread.

5. The combination in a circular knitting machine, provided with upper and lower coaxial knitting cylinders, separate stationary knitting cam mechanisms therefor, means for rotating said cylinders, a circular series of needles each provided with a hook and latch at each end, and a slider for each needle in each cylinder provided with knitting and transfer butts, of mechanism adjacent to the knitting cam mechanisms for feeding a non-elastic body thread to both the upper and lower cylinder needles to knit suc-

- cessive courses of rib knitting, drawdown cam mechanism for engaging the sliders of the upper cylinder to transfer the upper cylinder needles to the control of the lower cylinder sliders during 5 a plurality of revolutions of the cylinder, riser cam mechanism for raising the upper cylinder sliders during each revolution of the cylinders after the transfer of the upper cylinder needles to the lower cylinder, needle selecting mechanism 10 for bringing selected needles to a different level than intervening unselected needles, means for feeding an elastic thread under tension to the selected needles, means for bringing all of said needles to the same level and bringing the un- 15 selected needles outside of float portions of the elastic thread, and transfer cam mechanism for returning the upper cylinder needles to the upper cylinder before they reach the knitting cam mechanisms in each revolution of the cylinders. 20
6. The combination in a circular knitting machine, provided with upper and lower coaxial knitting cylinders, separate stationary knitting cam mechanisms therefor, means for rotating said cylinders, a circular series of needles each provided with a hook and latch at each end, and a slider for each needle in each cylinder provided with knitting and transfer butts, of mechanism adjacent to the knitting cam mechanisms for feeding a non-elastic body thread to both the upper and lower cylinder needles to knit successive 25 courses of rib knitting, drawdown cam mechanism for engaging the sliders of the upper cylinder to transfer the upper cylinder needles to the control of the lower cylinder sliders during each revolution of the cylinders, riser cam mechanism 30 for raising the upper cylinder sliders during a plurality of revolutions of the cylinders after the transfer of the upper cylinder needles to the lower cylinder, needle selecting mechanism for bringing selected needles to a different level than intervening unselected needles, means for feeding an elastic thread under tension to the selected needles, means for bringing all of said needles to the same level and bringing the unselected needles outside of float portions of the elastic thread, cam mechanism for lowering the sliders of the upper cylinder into position to engage the needles of the upper cylinder, and transfer cam mechanism 35 for retransferring the upper cylinder needles to the upper cylinder during a plurality of revolutions of the cylinder before they reach the knitting cam mechanisms, and means for preventing the needle selection in one or successive courses, the elevation of the sliders of the upper cylinder after the transfer of the upper cylinder needles to the lower cylinder facilitating the passage of the portion of the elastic thread between the last stitch in a preceding course in which it occurs and its feeding means, above the hooks of all the needles during the portion of the revolution 40 of the cylinder while they are all located in the lower cylinder.
7. The combination in a circular knitting machine, provided with upper and lower coaxial knitting cylinders, separate stationary knitting cam mechanisms therefor, means for rotating said cylinders, a circular series of needles each provided with a hook and latch at each end, and a slider for each needle in each cylinder provided with knitting and transfer butts, of mechanism adjacent to the knitting cam mechanisms for feeding a non-elastic body thread to both the upper and lower cylinder needles to knit successive 45 courses of rib knitting, drawdown cam mechanism for engaging the sliders of the upper cylinder to transfer the upper cylinder needles to the control of the lower cylinder sliders during each revolution of the cylinders, riser cam mechanism for raising the upper cylinder sliders during each revolution of the cylinders after the transfer of the upper cylinder needles to the lower cylinder, needle selecting mechanism for bringing selected needles to a different level than intervening unselected needles, means for feeding an elastic thread under tension to the selected needles, means for bringing all of said needles to the same level and bringing the unselected needles outside of float portions of the elastic thread, and transfer cam mechanism for returning the upper cylinder needles to the upper cylinder before they reach the knitting cam mechanisms during a plurality of revolutions of the cylinders, and pattern controlled mechanism for withdrawing the said drawdown and riser cams for the upper cylinder sliders to permit the knitting of continuous consecutive courses of rib knitting. 50
8. The combination in a circular knitting machine, provided with upper and lower coaxial knitting cylinders, separate stationary knitting cam mechanisms therefor, means for rotating said cylinders, a circular series of needles each provided with a hook and latch at each end, and a slider for each needle in each cylinder provided with knitting and transfer butts, of mechanism adjacent to the knitting cam mechanisms for feeding a non-elastic body thread to both the upper and lower cylinder needles to knit successive 55 courses of rib knitting, transfer mechanism for transferring all of the upper cylinder needles to the lower cylinder after the needles have received the non-elastic thread, the sliders of the lower cylinder having short transfer butts for spaced selected needles and long transfer butts for intermediate unselected needles, needle selecting mechanism comprising a drawdown cam for engaging the knitting butts of the lower cylinder sliders for the selected needles, and a second drawdown cam movable into position to engage the long transfer butts of the lower cylinder sliders for the unselected needles, and having a steeper pitch than the first mentioned drawdown cam, to bring the hooks of the unselected needles to a lower level than those of the selected needles, mechanism for feeding an elastic thread to the hooks of said selected needles, cam mechanism for bringing the hooks of all the needles to the same level, and bringing the unselected needles on the outside of the floated portions of the elastic thread between the selected needles, and transfer mechanism for returning the upper cylinder needles to the upper cylinder, before they reach the feeding point of the non-elastic body thread during a plurality of courses of knitting, a raising cam provided with a movable shunt portion for engaging the knitting butts of the lower cylinder sliders, and raising them into position to engage said drawdown cams, said second drawdown cam being movable to an inoperative position to permit the knitting of successive courses of rib knitting in the leg and foot of a stocking, and means for momentarily moving the shunt portion of said raising cam out of and into operative position to permit the said second mentioned drawdown cam to be moved into operative relation with the sliders of the lower cylinder between the knitting butts and transfer butts thereof, to avoid injury to the butts. 60
9. The combination in a circular knitting machine having coaxial rotatable needle cylinders superimposed one above the other, a circular 65
- 70
- 75

- series of needles having a hook and latch at each end, and sliders in each cylinder for engaging said needles and provided with knitting and transfer butts, of knitting cam mechanisms for 5 engaging the knitting butts of the sliders of both cylinders during a portion of the rotation thereof, and a thread feed finger for feeding an inelastic thread to the needles of both cylinders adjacent to said knitting cam mechanism to produce rib 10 knitting, transfer cam mechanism operative during a portion of each of a plurality of revolutions of said cylinders for transferring the upper cylinder needles to the lower cylinder, needle selecting mechanism for bringing spaced selected needles 15 of the lower cylinder needles to a different level from the intervening needles while all of said needles are in the lower cylinder, a thread feed finger for feeding a second thread to said selected needles only, and cam mechanism for 20 bringing said needles to the same level and bringing the unselected needles outside of the floated portions of said second thread between the selected needles, and transfer cam mechanism for retransferring the upper cylinder needles to the 25 sliders for the upper cylinder, in the same revolution of the cylinders before they reach the first mentioned thread feed finger.
10. The combination in a circular knitting machine having coaxial rotatable needle cylinders 30 superimposed one above the other, a circular series of needles having a hook and latch at each end, and sliders in each cylinder for engaging said needles and provided with knitting and transfer butts, of knitting cam mechanisms for 35 engaging the knitting butts of the sliders of both cylinders during a portion of the rotation thereof, and a thread feed finger for feeding an inelastic thread to the needles of both cylinders adjacent to said knitting cam mechanism to produce rib knitting, transfer cam mechanism operative 40 during a portion of each of a plurality of revolutions of said cylinders for transferring the upper cylinder needles to the lower cylinder, needle selecting mechanism for bringing spaced selected needles 45 of the lower cylinder needles to a different level from the intervening needles while all of said needles are in the lower cylinder, a thread feed finger for feeding an elastic thread to said selected needles only, cam mechanism for 50 bringing all the needles to a common level and bringing the unselected needles outside of the floated portions of elastic thread between se-

lected needles, transfer cam mechanism for transferring the upper cylinder needles to the upper cylinder in the same revolution of the cylinders, before they reach the first mentioned thread feed finger, means for throwing the needle selecting mechanism out of operation to permit the knitting of a course or courses of rib knitting without feeding the elastic thread, and permitting the elastic thread to pass over all the needles during the portion of the revolution of 10 the needle cylinders when all the needles are in the lower cylinder.

11. The combination in a circular knitting machine, provided with upper and lower coaxial knitting cylinders, separate stationary knitting cam mechanisms therefor, means for rotating said cylinders, a circular series of needles each provided with a hook and latch at each end, and a slider for each needle in each cylinder provided with knitting and transfer butts, of mechanism adjacent to the knitting cam mechanisms for feeding a non-elastic body thread to both the upper and lower cylinder needles to knit successive courses of rib knitting, drawdown cam mechanism for engaging the sliders of the upper cylinder to transfer the upper cylinder needles to the control of the lower cylinder sliders during each of a plurality of revolutions of the cylinders, riser cam mechanism for raising the upper cylinder sliders during each revolution of the cylinders after the transfer of the upper cylinder needles to the lower cylinder, needle selecting mechanism for bringing selected needles to a different level than intervening unselected needles, means for feeding an elastic thread under tension to the selected needles, means for bringing all of said needles to the same level and bringing the unselected needles outside of float portions of the elastic thread, a latch opener for engaging the needles after the feeding of said elastic thread to insure the engagement of the upper cylinder needles with their sliders, and to position the unselected lower cylinder needles to receive another course of inelastic thread, and transfer cam mechanism for returning the upper cylinder needles to the upper cylinder before they reach the knitting cam mechanisms in each revolution of the cylinders.
